(57) **CLAIM**

The ornamental design for a vial sleeve, as shown and described.

DESCRIPTION

FIG. 1 is a perspective view of a vial sleeve including a label disposed on the vial sleeve;

FIG. 2 is a front view of the vial sleeve of FIG. 1;

FIG. 3 is a rear view of the vial sleeve of FIG. 1;

FIG. 4 is a left-side view of the vial sleeve of FIG. 1;

FIG. 5 is a right-side view of the vial sleeve of FIG. 1;

FIG. 6 is a top view of the vial sleeve of FIG. 1;

FIG. 7 is a bottom view of the vial sleeve of FIG. 1;

FIG. 8 is a perspective view of the vial sleeve of FIGS. 1-7 disposed on a vial;

FIG. 9 is a perspective view of a vial sleeve including a label disposed on the vial sleeve;

FIG. 10 is a front view of the vial sleeve of FIG. 9;

FIG. 11 is a rear view of the vial sleeve of FIG. 9;

FIG. 12 is a left-side view of the vial sleeve of FIG. 9;

FIG. 13 is a right-side view of the vial sleeve of FIG. 9;

FIG. 14 is a top view of the vial sleeve of FIG. 9;

FIG. 15 is a bottom view of the vial sleeve of FIG. 9; and, FIG. 16 is a perspective view of the vial sleeve of FIGS. 9-15 disposed on a vial.

The dashed lines are included for the purpose of illustrating environment and form no part of the claimed design.

1 Claim, 14 Drawing Sheets
